Primary Examiner — Daniel Bui*(74) Attorney, Agent, or Firm* — Blank Rome LLP**(57) CLAIM**

The ornamental design for an electrical connector, as shown and described.

DESCRIPTION

FIG. 1 is a left rear perspective view of an electrical connector showing our new design. The right, rear perspective view is a mirror image thereto;

FIG. 2 is a left side elevation view thereof. The right side elevation view is a mirror image thereto;

FIG. 3 left, front perspective view thereof. The right, front perspective view is a mirror image thereto;

FIG. 4 is a front elevation view thereof; and,

FIG. 5 is a rear elevation view thereof.

The broken line portion of the figure drawings is included for the purpose of illustrating environment and forms no part of the ornamental design.
